UNITED STATES PATENT OFFICE.

SYLVESTER HUGH MILES, OF ROSSVILLE, KANSAS.

DOOR-CHECK.

SPECIFICATION forming part of Letters Patent No. 390,887, dated October 9, 1888.

Application filed July 23, 1888. Serial No. 280,737. (No model.)

To all whom it may concern:

Be it known that I, SYLVESTER HUGH MILES, a citizen of the United States, residing at Rossville, county of Shawnee, and State of 5 Kansas, have invented certain new and useful Improvements in Door Stops, of which the following is a specification.

My invention relates to a device which is adapted to be arranged in connection with a door, and so attached as to be operable by the door knob, the other end being provided with a moving latch suitably pivoted, which latch is adapted to catch or slip into a semicircular securing-plate placed upon the jamb or door- 15 frame.

My particular invention consists in a simplification of the various parts and the specific arrangements shown in the drawings, and pointed out in the claim.

Referring to the accompanying drawings, which form a part of the specification, Figure 1 is an elevation showing a door with my attachment applied. Fig. 2 is a detail perspective view of the said attachment.

In the drawings, A represents a door provided with a knob, B. The shank C of the door-knob is provided with a disk, D, having two small pins, E, upon one of the faces. These small pins extend outwardly and are 30 raised in the same horizontal plane and on the same side of the disk.

A yoke or Y-shaped lever, F, straddles the door-knob, the two branches of the yoke extending downwardly and in proximity to the 35 disk D. The branches of the yoke are provided with semicircular slots, and the yoke-shaped lever and disk are so arranged in regard to each other that the pins on the disk will extend through the slots on the lever, so that 40 by working the door-knob either to the right or to the left the disk, which rotates therewith, will cause the yoke to be drawn down by virtue of one or the other of the pins engaging in the bottom of its corresponding slot. The upper

45 part of the yoke or lever F is provided with two downwardly-extending fingers, G, between which is placed a rod, H, arranged to move slightly between the two fingers. This rod H

is set vertically, and is attached at its upper end to a bell-crank lever, J, which is pivoted 50 to the door by means of the bolt K. The other end of the bell-crank lever is swiveled to a horizontally-moving rod, L, which turns on and is pivoted at its upper end to the latch-lever N. The upper end of the latch-lever N is 55 adapted to engage in the serrations or openings provided in the outer edge or periphery of the securing plate M. This semicircular securing-plate is attached to the door jamb or frame, and as the door is swung around the knob, 60 being controlled by the hand, can be held down until the door is opened into the desired position, when the knob can be liberated and the locking lever slipped into one of the openings or serrations of the securing plate. 65

In connection with the various joints of the apparatus I arrange boxes R for covering the same, having in the sides thereof slots for the accommodation of the levers working therethrough. The advantage of this is that the 70 working parts are always kept clean and free from dust and are removable from said box, both of which are great advantages, and both of which are found desirable.

A spring, S, is provided for withdrawing 75 the levers and knob automatically to their normal positions if there happens to be any tension in the apparatus. By placing the yoke-shaped lever as shown and described it is hidden from view by the inclosing case and 80 by the door-knob, and thus the construction is desirable in this respect.

Having thus described my invention, the following is what I claim as new therein and desire to secure by Letters Patent: 85

The combination of a door-handle, a disk, D, having pin E, with a yoke-shaped lever, F, having slots, as shown, and fingers G at the upper end of said lever, the rod H, bell-crank J, pull-rod L, locking-lever N, and securing- 90 plate M, all arranged substantially as described, and for the purposes set forth.

SYLVESTER HUGH MILES.

Witnesses:

A. J. PARR,
PERRY WYATT.
